UNITED STATES PATENT OFFICE

HARRY B. JACKSON, OF LEBANON, NEW HAMPSHIRE, ASSIGNOR TO H. W. CARTER & SONS, OF LEBANON, NEW HAMPSHIRE, A CO-PARTNERSHIP CONSISTING OF HARRY B. JACKSON, STANLEY S. JACKSON AND JOHN J. LANDERS, ALL OF LEBANON, NEW HAMPSHIRE, L. F. FLETCHER, OF NEWTONVILLE, MASSACHUSETTS, AND G. E. COGSWELL, OF BROOKLINE, MASSACHUSETTS

OVERALLS

Application filed October 15, 1931. Serial No. 568,916.

This invention relates to overalls and pertains more particularly to improvements in the construction and arrangement of the side pocket of overalls, dungarees or like garments. The principal purpose of the invention is to provide a garment of this character in which a commodious and readily accessible side pocket is so attached to the inner of a front section of the garment that its slit or opening is located inside an opening at the side of the garment and hence is covered and concealed by the front section when the garment is in use.

In overalls heretofore manufactured, the so-called side pockets have had exterior openings formed as transverse or diagonal slits in the front of the garment. Pockets of this type tend to flare or gape open as the wearer bends or moves about and the edge of the pocket is thus liable to be caught by tools, parts of machines or other projecting objects whether fixed or movable. The consequent risk of personal injury, damage to the garment or machinery and inconvenience to the wearer of the common type of overall is obviated by the present invention without otherwise impairing the utility of the garment.

A recommended embodiment of this invention is illustrated in the accompanying drawing, in which

Fig. 1 is a front elevation of a pair of overalls equipped with the improved side pockets;

Fig. 2 is an enlarged fragmentary rear view of one side of the garment, the back section being folded down to illustrate the preferred arrangement of the pocket; and

Fig. 3 is an enlarged section on line 3—3 of Fig. 2 with parts beyond the plane of section omitted.

In making a garment according to this invention, the fabric pieces used in forming the top, body and leg portions may be cut from denim or like material and assembled in any common manner to produce a pair of over-

alls of the general character shown in Fig. 1. For example, the front 4, legs 5 and back 7 may be formed of two main fabric pieces stitched together along the median line 6 of the body portion of the garment; and the upper edges of the front and back sections may be connected by suitable shoulder straps 8 of ordinary construction.

The front and back sections 4 and 7 respectively are separated at opposite sides of the garment to provide opposed flaps 9 and 10 which define openings located approximately at the thigh part of the body portion between the respective sections, the front flap 9 having a facing strip 11 and the rear flap 10 being inturned and hemmed as at 12. The two flaps are preferably connected by a bottom seam at 13 and are separably held together at the upper end of the opening by fastening a button 14 of the rear flap in a buttonhole 15 of the front facing 11, so that the mouth of the side opening of the garment is normally constricted.

Each of the side pockets 16 is attached at its upper edge to the inside of the front section 4 of the garment, as by stitching 17, with the divided outer edge of the bag-like pocket located inside the garment opening and preferably spaced inwardly from the edge of the facing 11 and defining the vertical slit or mouth 18 leading directly into the pocket. The outer or side edge of the front part of the pocket fabric is preferably stitched between the garment section 4 and one of the hemmed edges of the facing strip 11 as shown at 19 of Fig. 3; and the opposite margin of the pocket slit is preferably furnished with a binding strip 20 having its lower end connected at the seam 13. The bottom of the pocket may hang freely below said seam, and it is apparent that the pocket may be made of any suitable material and in any practical size or shape.

The bound margin 20 of the pocket mouth 18 is preferably provided with the socket

part 21 of a snap fastener or the like, which cooperates with a stud part 22 attached to the hemmed edge 12 of the rear flap 10, whereby the rearward portion of the pocket may be 5 separably connected to the back section 7 of the garment. Hence, although the slit 18 leading directly into the pocket is spaced inwardly from the side margin of the garment front and is normally covered by one or both the overlapping flaps 9 and 10, the 10 pocket is readily accessible and the hand of the wearer is guided into rather than behind the pocket when it is inserted behind the faced margin 11 of the front section 4. It is thus apparent that the pocket mouth is 15 spaced inwardly from the mouth of the garment opening and is covered and concealed by the front section of the overall; so that it cannot protrude or flare open to catch upon machine parts or other equipment which may 20 be handled by the workman.

It will be understood that the improved pocket arrangement herein described in connection with a common form of overall, may 25 be utilized in outer garments generally and that the structural details herein illustrated may be varied to suit particular purposes without departing from the essence of this invention as defined in the following claims.

I claim:

1. In a garment having body and leg portions and front and back flaps located approximately at the thigh part of the body portion between front and back sections of 35 the garment, said flaps being separably connected at their upper ends and forming a normally constricted side opening of the garment, and a bag-like pocket attached to the inside of the front section and having a slit 40 along its outer edge, the top of the pocket being spaced below the upper ends of the flaps and said slit being located remote from the outer edge of the front flap so that the mouth of the pocket is spaced inwardly from 45 the mouth of the garment opening and is normally covered by the overlapping margins of the back and front flaps.

2. In a garment having body and leg portions and front and back flaps located approximately at the thigh part of the body portion between front and back sections of 50 the garment, said flaps being separably connected at their upper ends and forming a side opening of the garment, and a bag-like 55 pocket attached to the inside of the front section and having a slit along its outer edge, the top of the pocket being spaced below the upper ends of the flaps and said slit being located remote from the outer edge of the 60 front flap so that the mouth of the pocket is spaced inwardly from the mouth of the garment opening and is normally covered by the overlapping margins of the back and front flaps, the back flap being inturned and 65 joined at its lower end to the front flap and

to the lower end of the pocket slit, the in-turned margin of said back flap having a fastening element thereon, and the rearward part of the pocket having a complementary fastening element located adjacent its slotted edge whereby the back flap may be separably attached to said pocket part.

Signed by me at Lebanon, Grafton County, New Hampshire, this thirteenth day of October, 1931.

HARRY B. JACKSON.
